CLAIM

I claim the ornamental design for a workstation contractor saw module, as shown and described.

DESCRIPTION

FIG. 1 is a perspective view of my new design for a workstation contractor saw module as shown in the drawings;

FIG. 2 is a top view thereof;

FIG. 3 is a bottom view thereof;

FIG. 4 is a front view thereof;

FIG. 5 is a back view thereof;

FIG. 6 is a right view thereof; and,

FIG. 7 is a left view thereof.

The broken lines shown in the drawings represent unclaimed subject matter and form no part of the claimed design.

1 Claim, 7 Drawing Sheets
